REFRIGERATOR ARTICLE RECEPTACLE

Harold H. Gilbert, Mount Clemens, and John R. Reigle, Detroit, Mich., assignors, by mesne assignments, to Copeland Refrigeration Corporation, Mount Clemens, Mich., a corporation of Michigan

Application January 11, 1932, Serial No. 585,890

1 Claim. (Cl. 312—173)

This invention relates to the refrigeration art and has particular relation to the provision of suitable shelves and other supports in refrigerators for receiving and storing accessibly the 5 wide variety of sizes and shapes of products which a refrigerator is required to accommodate.

It is desirable in a refrigerator to have the products contained therein stored in such manner that they will be immediately accessible when 10 the refrigerator door is opened and without the necessity of removing products other than those at the time desired. If the refrigerator is simply provided with shelves they must be placed relatively far apart in order to accommodate products of relatively large size, in which event it is necessary to pile the smaller products one on top 15 of another and under which conditions it is relatively difficult to find and to remove any particular product which is desired.

20 If the bottom shelf of a refrigerator is made relatively short or of a variable depth and bottles or other tall products are placed on the bottom of the refrigerator in front of said shelf, it is of course impossible to obtain access to the space 25 therebehind until one or more of the bottles have been removed.

Among the objects of the present invention are to divide the interior of a refrigerator into a 30 plurality of sections or compartments each provided with article containers, shelves or racks designed to accommodate articles of approximately the same size and which containers, shelves or racks are separable from one another in order that access may be had to all articles or 35 products which the refrigerator may contain; to provide a refrigerator having relatively shallow and closely spaced shelves in front of which is a region for receiving other article containers which are removable from the refrigerator when 40 the door is opened and to which access may be had in a region remote from the shelves or supporting devices remaining permanently in the refrigerator; to provide a refrigerator containing relatively narrow or shallow shelves on which 45 small articles or food products may be stored near the back wall of a refrigerator and which are accessible without first removing larger articles permanently located in the refrigerator in front thereof; to render more efficient the use of 50 available space in the interior of a refrigerator by providing a relatively large amount of shelf area for articles of small size and throughout which area such articles may be distributed in such manner as to be readily accessible, and to 55 provide a relatively small amount of shelf area

or containers for large articles and in which area or containers such articles may be compactly and conveniently arranged; and in general to provide a refrigerator in which the convenience of the refrigerator owner will be served more completely than has been the case with refrigerators heretofore devised.

In the drawing:

Figure 1 is a vertical sectional view through a refrigerator adjacent one edge of a door opening therein and illustrating supports or receptacles for products to be stored secured both to the refrigerator door and to the side walls thereof.

Fig. 2 is a fragmentary, cross-sectional view of the refrigerator illustrated by Fig. 1 as it might appear looking downwardly from the plane of line 2—2 thereon.

Fig. 3 is an enlarged vertical sectional view taken substantially on line 3—3 of Fig. 2, and

Fig. 4 is a fragmentary, horizontal sectional view of one of the containers as it might appear from line 4—4 on Fig. 1.

Referring particularly to the drawing, the invention is embraced in a refrigerator 10 comprising a heat insulated cabinet 11 having a swing-insulated door 12 for closing an opening therein through which products to be stored are inserted and removed. The cabinet 11 also has disposed therein the cooling unit of any suitable refrigeration apparatus (not shown) and by 25 which water and other liquids may be frozen and the interior of the cabinet maintained at a relatively low temperature.

Arranged on the side walls of the cabinet 11 are a plurality of shelf supports 14 on which refrigerator shelves 16 are retained. These shelves are somewhat narrower or more shallow than shelves ordinarily employed in refrigerators to provide a region or space in front thereof for the accommodation of large articles such as bottles, 40 melons, vegetables, etc., which ordinary shelves are not particularly adapted to support.

The bottom shelf ordinarily should be spaced a considerable distance from the bottom wall of the refrigerator in order to make room for the disposition therebeneath of large containers or articles of merchandise which it may be desirable to place there. Space for this purpose also may be provided by removing one of the refrigerator shelves located adjacent the bottom refrigerator 50 wall when it is desired to store large articles in such space and at other times the shelf may be replaced and employed in the refrigerator when a large number of small articles are to be accommodated.

- The remaining refrigerator shelves are disposed relatively closely together in order to provide a large amount of shelf area for storing relatively small products and vessels.
- 5 In the space in front of the shelves is located a plurality of containers or receptacles 17, 18 and 19 which are secured either permanently or removably in spaced relation upon the inside of the refrigerator door 12.
- 10 The lower one 17 of these containers or receptacles embraces a pair of spaced and vertically disposed bars or frame members 21 and 22 which are supported upon a metallic lining 23 of the refrigerator door 12 by stud bolts 29 projecting through the upper and lower ends thereof and secured in position by cap nuts 24. Annular collars 26 are disposed between the bars and the lining in order to maintain such elements in properly spaced relation. Inside the lining 23 and directly opposite the bars 21 and 22 are disposed brackets 27 which are so flanged at opposite ends, as indicated at 28 in Fig. 4, as to receive therein the heads of the studs 29 and to prevent their rotation.
- 15 At the upper and lower extremities of the bars 21 and 22 are secured, as for example by welding, a pair of rectangular frames 31 and 32 respectively, which are formed by properly bending and securing together the ends of a pair of long rods.
- 20 The two front corners of the frames 31 and 32 are secured rigidly together by rods 33 at the opposite ends of which the frames are welded or otherwise secured. Welded or otherwise secured to the front of the bars 21 and 22 and the rods 33 and suitably spaced between the frames 31 and 32 are a plurality of side members 34 which are formed of relatively light strips bent in rectangular formation.
- 25 In order to prevent rattling of milk bottles or other similar articles disposed therein, one or more of the side members 34, or other parts of the structure, may be covered with removable rubber bumper strips as is illustrated at 36 which are so molded or otherwise formed as to substantially surround the members on which they are disposed, thus preventing engagement therewith of the articles within the container. In order to permit bending at the corners an outer portion of the bumper strip 36 is cut away as is indicated at 37 in Fig. 4. Also as is indicated by this figure the side members 34 supporting bumper strips are bent inwardly as is indicated at 38 until the outer bumper strip edges are substantially flush with the side members not provided with bumper strips.
- 30 The bottom of the container is formed by a shallow pan, vessel or receptacle 39 having outwardly flanged edges 41 adapted to be removably disposed on the side portions of the lower frame 32.
- 35 In order to avoid a condition in which articles or vessels placed on the bottom of the refrigerator might interfere with the location of container 17 the refrigerator lining 42 at the bottom wall thereof is provided with an upwardly projecting rib or bead 43 which is positioned adjacent the outer edge of the container to indicate to the refrigerator user how far forwardly such articles may be permitted to extend.
- 40 The containers 18 and 19 disposed above the container 17 may be formed by an upward continuation of the frame of the container 17 or they may be formed separately as indicated. In the present instance the container 18 is substantially identical to the container 17 and hence the same reference characters and detailed description may be considered as applying to both containers. It is located just far enough above the container 17 that bottles and other articles may be easily removed from the latter, and is adapted to receive fruit, packages or other similar products.
- 45 The container 19 located above the container 18 secured to the refrigerator door by fastening elements similar to those employed in securing the containers 17 and 18 to the door and to all which elements corresponding reference numerals are applied. This container consists of a solid walled receptacle having openings 46 formed adjacent the upper open side thereof and through which air may circulate between the interiors of the receptacle and the refrigerator. The open other upper side of the receptacle is adapted to be closed by a cover 47 hinged as indicated at 48 to the inner wall thereof to prevent displacement of the cover when the refrigerator door is violently closed. The container 19 may be employed for receiving vegetables or other products having a tendency to become shriveled and dried when exposed to the circulating air in a refrigerator and for keeping such products in a moist and well preserved condition.
- 50 Any number of containers may be secured to a refrigerator door and behind such containers any desired number of shallow shelves may be employed. Any remaining space may be occupied by shelves similar to those now employed in refrigerators and extending from the front to the rear thereof.
- 55 In the structure disclosed herein, when the refrigerator door is opened a large part of the contents of a refrigerator swings outwardly with the door and is thereupon accessible for removal from the containers supported by the door. The remainder of the products stored in the refrigerator are also conveniently removable from the narrow shelves permanently secured therein by reason of the removal with the door of the large and bulky products heretofore supported by the shelves.
- 60 While the structure herein disclosed constitutes a preferred form and application of the invention, it is to be understood that other structures differing widely from that herein disclosed are within the scope of the invention defined by the appended claim.
- 65 We claim:
- A refrigerator comprising an insulated cabinet having a door opening, a door for said opening, an article container comprising upper and lower frame members secured on the inside of said door, and a pan having flanged edges supported on the lower one of said frame members and providing a bottom closure member for said container.

HAROLD H. GILBERT.
